UNITED STATES PATENT OFFICE.

JOHN J. SPENCE, OF GREENVILLE, TEXAS, ASSIGNOR OF ONE-HALF TO WILLIAM W.
ALSOBROOK, OF GREENVILLE, TEXAS.

ARMORED CAR.

1,249,542.

Specification of Letters Patent.

Patented Dec. 11, 1917.

Application filed May 22, 1917. Serial No. 170,244.

To all whom it may concern:

Be it known that I, JOHN J. SPENCE, a citizen of the United States, residing at Greenville, in the county of Hunt and State of Texas, have invented a new and useful Armored Car, of which the following is a specification.

The present invention appertains to an armored car or portable fort, and aims to provide a novel and improved armor unit of that nature.

It is the object of the invention to provide a portable structure for housing a crew and protecting them from the weather as well as shell fire, and the like, and providing a formidable fort, which can be run over ordinary roads from place to place for offensive or defensive operations. The device serves as a protection for the gunners, operators, and other men of the crew, and the structure can contain a number of machine guns, small cannons, regular army guns and other ordnance and equipment, whereby devastating fire of projectiles in various directions can be accomplished, while bullets, shell fragments and other ordinary projectiles are deflected or glanced from the armor plate.

A further object of the invention is the provision of a novel turret for the effective firing of small cannons, machine guns, rifles and other firearms, and for the protection of the operators and attendants.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawings, wherein:

Figure 1 is a perspective view of the armored car.

Fig. 2 is a longitudinal section thereof.

Fig. 3 is a plan view of the structure, part of the turret being broken away.

In carrying out the invention, there is provided a suitable deck or platform 1 mounted on wheels 2 or other suitable run-

ning gear, whereby the car can be readily propelled from place to place by means of a suitable engine 3 carried by the deck, preferably at the forward end thereof, in accordance with prevailing automobile practice, although any suitable engine can be used at a suitable protected point of the car. The car has a suitable steering gear controlled by a hand wheel 4 or other operating member, and disposed behind an armor plate dash 5 upstanding from the deck 1 near the forward end thereof. This dash is of cowl formation, being provided with the roof 7 and sides 8 of armor plate, to provide a compartment 11 for the operator, the dash 5 having an opening or window 10, to enable observations to be made. One side of the cowl dash has a door 9 for admitting the crew, said door being armored. An armored hood 6 is supported by the deck 1 in front of the dash for protecting the engine from shell fire.

Immediately in rear of the compartment 11 is a main compartment 12, divided from the compartment 11 by a transverse partition 13, said compartment 12 having a rear transverse partition 14, a roof 15, and side walls 16, all of which parts are of armor plate. The side walls 16 are bulged outwardly, so that the upper and lower portions are inclined, for deflecting projectiles, and the ridge portions of said side walls are provided with port holes 17 through which the firearms, such as machine guns, small cannon, and the like, can be projected for firing toward the opposite sides in various directions. The partition 13 is provided with a door 18 for admitting the crew from the compartment 11 into the main compartment 12, and the partition 14 has a door 19 through which the men can pass.

An armored tower or dome 20 is mounted on the roof 15 of the compartment 12 for observation purposes, although the port holes 21 of the tower permit of the firing of rifles or other firearms therefrom. The roof 15 is provided with a trap-door 22 admitting the men from the compartment 12 into the observation tower and, if desired, a ladder 23 can be provided to enable the men to readily ascend into and descend from the observation tower.

Mounted on the rear portion of the deck 1

is a turret having the floor 24 mounted for rotation on the deck, said deck having a pivot 25 for said floor, whereby the turret is pivoted for rotation about a vertical axis. 6 The turret has upstanding side walls 26 united with the floor, the forward portions of said side walls being extended upwardly to about the same height as the compartment 12, and having a roof or cover 27, the 10 rear portion of which is inclined for deflecting projectiles upwardly. The upper portion of the turret in rear of the roof 27 is open.

In order to turn the turret, a drum 28 is mounted for rotation in any suitable manner upon the deck 1; the floor 24 of the turret terminating short of the forward ends of the side walls 26, whereby the drum 28 can be mounted between said side walls near 20 the forward end of the turret. The drum 28 has a hand-wheel 29 or other suitable operating means, and a cable 30 has its ends attached to the forward ends of the side walls 26, and the intermediate portion of the 25 cable is wound around the drum 28, whereby the drum in being rotated in opposite directions, will move the forward portion of the turret forward one side or the other, to bring the turret to the desired angle.

Carried by the rear end of the turret is a shield 31 of armor plate, for protecting the gunners, said shield being of V-shaped section, and having the diverging top and bottom plates 32, and the side plates 33. The 35 angle or ridge portion of the shield 31 is provided with a suitable number of port holes 34 through which the barrels of the guns can be fired. The rear edge of the bottom plate 32 of the shield 31 is hinged, 40 as at 35, upon the floor 24 of the turret near the rear end thereof, whereby the shield 31, which is disposed transversely, can be swung about a transverse axis. The shield 31 is swung upwardly and rearwardly when giving battle, the rear portion of the shield being open to accommodate the gunners, who will be protected by the shield from the fire of the enemy. The shield 31 can be swung forwardly and downwardly to seat on the 45 turret between the side walls 26 thereof, as seen in dotted lines in Fig. 2, and may be used for housing and protecting ordnance, ammunition, and the like.

As a means for swinging the shield 31, 55 two cables 36 are attached thereto near the rear end of the top plate 32 and said cables are preferably trained or wound around guide pulleys 37 carried by the side walls 26, from which the cables 36 extend to and 60 are wound upon drums 38 adapted to be operated by hand, and carried by the opposite side walls 26 under the roof 27. When the shield 31 is in rearwardly swung position, the cables 36 in being wound upon the 65 drums 38 will swing the shield 31 upwardly

and rearwardly, so that it will swing onto the floor 24 of the turret, and when the turret is on the floor, the cables 36 in being wound up will swing the turret upwardly so that it can be readily swung into place for firing. The angle of the shield 31, during firing, can be regulated by rotating the drums 38 to wind up or unwind the cables 36, and when the shield is in upright position, as seen in dotted lines in Fig. 2, it is 75 effective for housing gunners when firing at enemy airships.

Having thus described the invention, what is claimed as new is:—

1. An armored car embodying a wheel 80 mounted deck, an armored cowl dash thereon having an observation opening and a door at one side, a main compartment on the deck in rear of said dash having a partition between it and the compartment of the dash, 85 said partition having a door, the sides of the said compartment having port holes, a turret mounted on the deck in rear of the main compartment, main compartment having a door for access to the turret, and an 90 observation tower mounted on the main compartment.

2. An armored car having a deck, a turret mounted on the deck, and a shield having an open portion and an opposite port hole, 95 the open portion of the shield being hinged to the turret, so that the shield can be swung to various positions and onto the turret in an upright position with its open portion lowermost.

3. An armored car having a deck, a turret having a floor pivoted on the deck and side walls upstanding from the floor, a shield having an open portion and an opposite port hole, the open portion of the shield 105 being hinged on said floor so that the shield can be swung away from the floor in various positions, said shield being swingable onto the floor with its open portion lowermost, and being swingable between said side walls. 110

4. An armored car having a deck, a turret rotatable upon the deck, a shield having an open portion and an opposite port hole, the open portion of the shield being hinged on the turret, the shield being swingable onto 115 the turret with its open portion lowermost, and means carried by the turret for swinging said shield toward and away from the turret.

5. An armored car having a deck, a turret 120 having a floor pivoted on the deck, and side walls upstanding from the floor, the side walls being raised at one end, a protecting roof carried by said raised portions of the side walls, the upper portion of the turret 125 being open between said raised portions and the other ends of the side walls, a shield having an open portion and an opposite port hole, the open portion of the shield being hinged on said floor adjacent to the last 130

mentioned ends of the side walls to swing outwardly and to upright position on said floor with its open portion lowermost and with the shield between the side walls, and
5 means below said roof for turning the tur-
ret and swinging the shield.

In testimony that I claim the foregoing

as my own, I have hereto affixed my signa-
ture in the presence of two witnesses.

JOHN J. SPENCE.
